UNITED STATES PATENT OFFICE.

AUGUSTE L. SALTZMAN, OF EAST ORANGE, NEW JERSEY, ASSIGNOR, BY MESNE ASSIGNMENTS, TO THE AMERICAN MULTIGRAPH COMPANY, A CORPORATION OF OHIO.

PRINTING-PRESS.

1,094,024.

Specification of Letters Patent. Patented Apr. 21, 1914.

Application filed May 29, 1905, Serial No. 262,850. Renewed June 21, 1913. Serial No. 775,134.

To all whom it may concern:

Be it known that I, AUGUSTE L. SALTZMAN, a citizen of the United States, residing at East Orange, in the county of Essex and 5 State of New Jersey, have invented new and useful Improvements in Printing-Presses, of which the following is a specification.

The invention relates to printing presses and, more particularly, to supports for 10 printing surfaces.

An object of the invention is to provide a support for a printing surface, for use on presses having a rotary printing member, which support shall be of light and rigid 15 construction, and which is held firmly in position but is capable of being easily removed. These and other objects of the invention will more fully appear from the following description.

20 The invention consists in the novel parts, improvements and combinations herein shown and described.

The accompanying drawings, referred to herein and forming a part hereof, illustrate 25 one embodiment of the invention, the same serving in connection with the description herein to explain the principles of the invention.

Of the drawings: Figure 1 is a perspective 30 view of a printing surface support; Fig. 2 is an end view of such a support mounted on the press cylinder; Fig. 3 is a side elevation corresponding to Fig. 2; Fig. 4 is a side elevation of a press cylinder of a form adapted 35 for use with a printing surface support, such as is shown herein; Fig. 5 is a section showing forms of transverse web; Fig. 6 shows one form of attaching the printing surface to its support; and Fig. 7 is a detailed view 40 of a portion of the mechanism.

In the embodiment of the invention illustrated herein a printing surface support 1 is shown which is in the general form of a section of a hollow cylinder. The said support 45 is adapted for use with a printing surface of any nature, such as relief, intaglio or planographic. It is illustrated herein, however, as used with a planographic surface. The material of which the said support is made may 50 be of such a nature as to form part of a planographic printing surface and may constitute the ink-rejecting or non-design part thereof. In the form shown in Fig. 1 of the drawings a surface of this nature is contem- 55 plated and is indicated by the reference nu-

meral 2. In the form shown in Fig. 6 of the drawings the printing surface is carried upon a separate plate which is mounted upon the support in a manner known to the art. The said support 1 is provided with transverse webs 3 which may be placed at the ends of the said support and may also be placed intermediate of the ends. These webs are so disposed and proportioned as to give the plate proper rigidity against flexure or deformation from handling, or from yielding while under impression. While the said support may be thus constructed sufficiently strong in itself to withstand all pressures and strains incident to use, a form of cylinder especially designed for use with a printing surface support of this character, and which acts to take up a large part of the strain and pressure during the impression, is provided. The cylinder is shown with portions 4 of such radius as to fit snugly within said support 1 so as to take up the squeeze of the impression so that there may be no yielding or deformation of the said support. The said cylinder is provided with recesses 5 at 60 the ends thereof for taking in the end transverse webs 3 of the support, and where there are internal transverse webs carried by the support transverse recesses 6 in the cylinder are provided for receiving same. These various corresponding parts are made to fit 65 each other in an exact manner, and thus it will be seen that the cylinder 4 backs up the support 1 in such manner as to prevent any deformation or yielding from the squeeze of 70 impressions and the support is also held in exact register in every respect. Holding means, in addition, may be provided and are shown as a pin 7 upon the support 1 and hook 8 upon the cylinder 2. The said hook 75 may be provided with a slot 9 in which a tap bolt 10 takes to hold it in either the engaging or disengaging position, the said hook being swiveled upon the pivot 11. The said support may be constructed of any suitable material such as steel and the said material may 80 be prepared for planographic printing or a planographic metal, such as zinc or aluminum, may be deposited thereon in suitable manner, as by electro-deposition or by dipping and a suitable design may be imposed 85 thereon in any desired manner.

From the foregoing it will be seen that a printing surface support has been provided 90 which is of great strength and rigidity while 95 100 105 110

at the same time possessing great lightness; that a press cylinder has been provided especially adapted for use with the said surface support; that the said cylinder takes up directly the strain or pressure of the impression; that the said support is held in exact register by the said cylinder, and is yet readily removable therefrom when desired, as well as possessing other advantages.

10 The invention, in its broader aspects, is not limited to the particular constructions shown, nor to any particular constructions by which it has been or may be carried into effect, as many changes may be made in the 15 construction without departing from the main principles of the invention and without sacrificing its chief advantages.

What I do claim as my invention and desire to secure by Letters Patent, is:

20 1. The combination with a printing surface support in the form of a section of a hollow cylinder and being provided with a transverse web, of a press cylinder having a portion of such radius as to fit within the 25 said printing surface support so that the concave surface of the support rests directly upon the cylinder.

2. The combination with a printing surface support in the form of a section of a hollow cylinder and being provided with a transverse web, of a press cylinder having a portion of such radius as to fit within the 30 said printing surface support, said cylinder also having a transverse recess for receiving the said web.

3. The combination with a printing surface support in the form of a section of a hollow cylinder provided with transverse webs at the ends thereof, of a press cylinder 40 having a portion of such radius as to fit within the said printing surface support and having shoulders or projections at the ends whereon the said transverse webs of the printing surface support may rest.

45 4. The combination with a printing surface support in the form of a hollow cylinder and provided with a plurality of transverse webs, of a press cylinder having a portion of such radius as to fit within the said 50 printing surface support and having transverse recesses for receiving the transverse webs of the said printing surface support.

5. The combination with a printing surface support in the form of a section of a hollow cylinder provided with webs upon the concave side thereof and arranged perpendicularly to the axis thereof, of a press cylinder having a portion of such radius as to fit within the said printing surface support, and having transverse recesses for receiving the webs upon the printing surface support, and having cut-away shoulders or projections at the ends thereof for supporting certain of the said webs.

65 6. The combination with a printing sur-

face support in the form of a section of a hollow cylinder provided with webs upon the concave side thereof and arranged perpendicularly to the axis thereof, of a press cylinder having a portion of such radius as to fit within the said printing surface support, so as to afford a backing therefor, a pivoted hook upon one of the said members, means adapted to be engaged by the hook on the other of said members, and means for holding the said hook in engaging position.

7. A support for a printing surface including in combination a member in the form of a section of a hollow cylinder, reinforcing means connected thereto, and means on said member for holding a flexible printing plate, said reinforcing means being arranged also to keep the support in place upon the cylinder.

8. The combination with a support for a printing surface in the form of a section of a hollow cylinder and having reinforcing means on the concave side thereof, of a cylinder shaped to fit within and to contact with the concave surface of said printing surface support.

9. The combination with a support for a printing surface in the form of a section of a hollow cylinder and having a plurality of webs on the concave side, of a cylinder having recesses to receive said webs and being shaped to contact with and support the inner side of said printing surface support between the webs.

10. The combination of a rotatable structure, a removable segment formed to carry a printing surface, transverse webs on the concave side of the segment, the rotatable structure having seats for the segment on the outer sides of the webs, and having space occupied by said webs.

11. The combination of a rotatable structure, a removable segment having means on its convex side for carrying a printing device and having a transverse web on its concave side, said rotatable structure being formed to support the concave side of the segment and having space for the web, and a hook for removably locking the rotatable structure and segment together.

12. The combination of a rotatable structure having cylindrical supporting surfaces, a removable segment adapted to seat on said surfaces, transverse stiffening webs on the concave side of the segment, there being space on the rotatable structure to accommodate said webs, a printing surface on the convex side of the segment, and means for locking the segment to the rotatable structure.

13. The combination of a member having a pair of partially cylindrical supports, a removable segment, the concave side of which is adapted to rest directly on said sup-

- ports, a transverse stiffening web rigid with the segment on its concave side and adapted to stand between said supports on the member, and means for locking the segment to 5 the member.
14. The combination, with a support for a printing surface in the form of a section of a hollow cylinder having a plurality of webs on its concave side, and a cylinder-like 10 member having space to receive said webs and being shaped to contact with and support the concave side of said printing surface.
15. The combination, with a support for 15 a printing surface in the form of a section of
- a hollow cylinder having a plurality of webs on its concave side, a cylinder-like member having space to receive said webs and being shaped to contact with and support the concave side of said printing surface, and a hook 20 carried by one of said members and adapted to engage the other.
- In testimony whereof I have signed my name to this specification in the presence of two subscribing witnesses.
